VACUUM CLEANER UNIT

Raoul A. Lambert, Springfield, Mass., assignor to Westinghouse Electric Corporation, a corporation of Pennsylvania

Application June 24, 1952, Serial No. 20,330

Term of patent 14 years

(Cl. D9—2)

FIG.1.

FIG.2.

FIG.3.

To all whom it may concern:

Be it known that I, Raoul A. Lambert, a citizen of the United States, residing at Springfield, in the county of Hampden and State of Massachusetts, have invented a new, original, and ornamental Design for a Vacuum Cleaner Unit, of which the following is a specification, reference being had to the accompanying drawing, forming a part thereof.

Fig. 1 is a front perspective view of a vacuum cleaner unit incorporating my new design;

Fig. 2 is a side elevational view thereof; and

Fig. 3 is a front elevational view thereof.

The dominant features of the design reside in the portions shown in full lines.

I claim:

The ornamental design for a vacuum cleaner unit, substantially as shown and described.
